UNITED STATES PATENT OFFICE

158,117

FOLD-AWAY TRAY TABLE

Carl G. Nesbitt, Forest Hills, N. Y.

Application April 8, 1948, Serial No. 145,597

Term of patent 7 years

(Cl. D33—14)

To all whom it may concern:

Be it known that I, Carl G. Nesbitt, a citizen of the United States, residing at Forest Hills, New York city, in the county of Queens and State of New York, have invented a new, original, and ornamental Design for a Fold-Away Tray Table, of which the following is a specification, reference being had to the accompanying drawing, forming part thereof.

I claim:

The ornamental design for a fold-away tray table as shown.

CARL G. NESBITT.
